BERNHARD KELLER, OF DUISBURG-MEIDERICH, GERMANY, ASSIGNOR TO MASCHINEN-FABRIK THYSSEN & CO., AKTIENGESELLSCHAFT, OF MÜLHEIM-ON-THE-RUHR, GERMANY.

MOLDING-MACHINE.

1,129,873.

Specification of Letters Patent.

Patented Mar. 2, 1915.

Application filed May 5, 1913. Serial No. 765,527.

To all whom it may concern:

Be it known that I, BERNHARD KELLER, a subject of the Emperor of Germany, and a resident of Duisburg-Meiderich, Germany, have invented certain new and useful Improvements in Molding-Machines, of which the following is a specification.

This invention relates to machines for use in producing molds in condition to receive the molten metal in foundry work and the like and it comprises means for jarring the forms for the purpose of packing the sand in the mold.

There are machines of the kind described already known in which the packing of the sand is effected by blows applied by a hammer to the under side of the mold support or a part rigidly connected therewith. In these machines the working movement is produced by compressed air which is introduced immediately underneath the hammer and is allowed to escape after each stroke. The air, however, introduced underneath the hammer cannot at first act with full power and a relatively large stroke of the hammer is therefore necessary in order to produce a sufficient acceleration of the movement of the hammer to obtain a sufficient jarring of the mold support.

The invention now consists in allowing the compressed air to act on the hammer with full power from the beginning. As the hammer therefore has to make only a fraction of the movement that is necessary in the known machines of this kind, the new construction of the machine guarantees great saving in power consumption.

The object of the invention may be attained by retaining the hammer in its lowest position until the compressed air or similar power introduced thereunder has reached its full pressure, whereupon the retaining catch is released and the hammer suddenly exposed to the influence of the compressed air. Whether tension or compression springs are used, they are fastened at one end to the hammer, which is at first being held down, while the opposite end of each spring is moved upward. On being subsequently released, the hammer rushes quickly upward, actuated by the springs.

Another manner of attaining the object of the invention consists in first moving the hammer downward in any desirable way, thereby causing the compression of an air or

spring cushion. As soon as the power, pressing the hammer downward ceases, this cushion imparts to the hammer its working movement. The resistance of the cushion which is increased during the downward movement of the hammer, may also be renewed by the supply of additional compressed air during the upward movement of the hammer or be kept at an equal pressure.

The subject matter of the invention is illustrated in the drawings in several different embodiments and:—Figure 1 shows a vertical section of a molding machine; Fig. 1^a a partial section similar to Fig. 1 slightly modified; Fig. 2, a view similar to Fig. 1 of a second modification; Fig. 3, a third embodiment of the invention also in vertical section but in larger scale and; Fig. 4, a fourth embodiment in a view similar to Fig. 3.

In Fig. 1 a guiding piston *b* is rigidly connected with the mold support *a*. A hammer *c* slides upon said piston *b* which hammer is guided in its turn by the stationary casing *d*. The mold support *a* can either be firmly supported or rest on an air cushion *p*, see Fig. 1^a, or as illustrated in Figs. 2 to 4, it may be supported by rods and springs. Several pistons *q*¹ connected to the hammer by means of piston rods *s*, Fig. 1, are used for the drawing down of the hammer *c* which pistons move in cylinders *r* and are actuated by compressed air or like means. The spring cushion which actuates the upward throw of the hammer *c* consists here of springs *g* which may also be assisted by an air cushion *t* situated under the hammer *c*. A similar air cushion may also be provided under the piston *q*. The inlet and outlet of the compressed air, here assumed as motive power, is regulated by means of a valve gear *k*.

The operation of the machine proceeds as follows:—The compressed air, entering the cylinders *r* by means of the valve gear *k*, moves the pistons *q*¹ downward and subsequently the hammer *c* by means of the rods *s*, whereby the springs *g* with or without the air cushion *t* are compressed. The mold support *a* is immovably held in its suspended position during this time either supported by the table extension at the top as in Fig. 1; or by the air cushion *p* as in Fig. 1^a; or by the rods suitably provided with springs as shown in Figs. 2 to 4. After the

hammer *c* has moved a certain distance downward, the valve gear *k* works to prevent the further entrance of compressed air into the cylinders *r* and therefore opens the exhaust for it into the atmosphere. Through this, the forces stored in the springs and air cushions, working underneath the hammer, are released, throwing the hammer with great violence upward 10 against the previously stationary mold support *a*, causing a jarring of the molding boxes, which have been placed on the mold support whereby the packing of the sand in the boxes is attained. After the knocking 15 of the hammer *c* against the buffer or buffers *o* fixed to the mold support *a*, the inlet in the cylinders *r* above the piston *q* is again opened so that the whole process may be repeated.

20 In Fig. 2 the mold support, when at rest, is kept in position by means of a number of rods *u* together with springs *e* and *f*; the springs permitting of an adjustment of the position of the mold support. The supply 25 of air is again regulated by means of a valve gear *k*. The compressed air enters here between the guide piston *b* and the hammer *c* through the canal *h*. As the piston is drawn down by means of the springs *f*, the hammer 30 goes downward under the action of the air.

In Fig. 3, the canal *h*, for the entrance of the air, is arranged between the hammer *c* and a piston *i* which is rigidly connected 35 with the stationary casing *d* and which is also guided in the hammer cylinder surrounding the guide piston *b* so that the hammer is again pressed downward. It is however not necessary that the parts of the hollow cylinder which guide the pistons *b* and *i* possess the same diameters.

In Fig. 4 the hammer *c* is formed on the outside into a stepped piston. The air works on the step ring *n* underneath the 45 bushing *m* inserted in the casing *d* and, as the casing is a fixture the hammer must move downward.

The machine may also be constructed as a lifting carrier, turn-plate, or stripping 50 machine.

I claim:—

1. In a jarring molding machine, a mold 55 table, a reciprocating hammer, and a housing therefor, said hammer constructed to beat against said molding table from below, means providing a resilient support for said hammer, means by which said resilient support is caused to act with full force upon said hammer at the beginning of each stroke.

2. In a jarring molding machine, a mold 60 table, a reciprocating hammer and a housing therefor, said hammer constructed to beat against said mold table from below, means 65 providing a resilient support for said

hammer, means for retaining the hammer in its lowermost position until said resilient support has accumulated its greatest power.

3. In a jarring molding machine, a mold 70 table, a reciprocating hammer and a housing therefor, said hammer constructed to beat against said mold table from below, means providing a resilient support for said hammer, means for moving the hammer downward thereby accumulating power in 75 the resilient support for subsequently acting upon the hammer.

4. In a jarring molding machine, a mold 80 table, a reciprocating hammer and a housing therefor, said hammer constructed to beat against said mold table from below, a resilient support adapted to hold the mold table in a predetermined normal position, and means by which said resilient support is caused to act with full force upon said 85 hammer at the beginning of each stroke.

5. In a jarring molding machine, a mold 90 table, a reciprocating hammer and a housing therefor, said hammer constructed to beat against said mold table from below, a resilient support adapted to hold the mold table in a predetermined normal position, and means by which said resilient support is caused to act with full force upon said 95 hammer at the beginning of each stroke; and means for adjusting the predetermined normal position.

6. In a jarring machine, a mold table, a reciprocating hammer and a housing therefor, said hammer constructed to beat against 100 said mold table from below, means providing a resilient support for said hammer, external members for moving said hammer downward thereby accumulating power in 105 the resilient support for subsequently acting upon the hammer.

7. In a jarring molding machine, a mold 110 table, a reciprocating hammer and a housing therefor, said hammer constructed to beat against said mold table from below, means providing a resilient support for said hammer, means for moving the hammer downward thereby accumulating power in the 115 resilient support for subsequently acting upon the hammer, a chamber in said hammer, a piston working in said chamber, said piston being rigidly connected with said mold table, means for introducing a pressure medium into said chamber to act between said piston and said hammer, means for retaining said mold table in a substantially stationary position relative to said housing, whereby said hammer will be forced downward on the admittance of said pressure medium.

8. In a jarring molding machine, a mold 120 table, a reciprocating hammer and a housing therefor, said hammer constructed to beat against said mold table from below, means providing a resilient support for said 125 hammer.

mer, means for moving the hammer downward thereby accumulating power in the resilient support for subsequently acting upon the hammer, a chamber in said hammer; a 5 piston working in said chamber, said piston being rigidly connected with said housing, means for introducing a pressure medium into said chamber to act between said piston and said hammer; means for retaining said 10 mold table in a substantially stationary position relative to said housing, whereby said hammer may be forced downward on the admittance of the pressure medium.

9. In a jarring molding machine, a mold 15 table, a reciprocating hammer and a housing therefor, said hammer constructed to beat against said mold table from below, means providing a resilient support for said hammer, means for moving the hammer downward 20 thereby accumulating power in the resilient support for subsequently acting upon the hammer, a chamber formed between said hammer and said housing, means for introducing a pressure medium into said chamber 25 to act between said housing and said hammer, means for retaining said mold table in a substantially stationary position relative to said housing, whereby said hammer will be forced downward on the admittance of 30 said pressure medium.

10. In a jarring molding machine, a mold

table, a reciprocating hammer and a housing therefor, said hammer constructed to beat against said mold table from below, means providing a resilient support for said hammer, means for moving the hammer downward 35 thereby accumulating power in the resilient support for subsequently acting upon the hammer, means for retaining the mold table in its normal position, said means comprising resilient members permitting a slight movement in opposite directions out of said normal position.

11. In a jarring molding machine, a mold 40 table, a hammer coaxial with said mold table and forming a guide therefor, a housing enclosing said hammer and permitting reciprocating movement of the hammer relative to the housing, resilient means acting on said hammer and tending to press the hammer 45 against said mold table, a pressure chamber in connection with said hammer, and means for admitting pressure medium into said chamber, thereby moving said hammer against the power of said resilient means. 50

The foregoing specification signed this 55
14th day of April, 1913.

BERNHARD KELLER.
